CLAIM

The ornamental design for a seat for exercise machines, as shown and described.

DESCRIPTION

FIG. 1 is a front perspective view of a seat for exercise machines showing our new design.

FIG. 2 is a rear perspective view thereof.

FIG. 3 is a front elevational view thereof.

FIG. 4 is a rear elevational view thereof.

FIG. 5 is a left side elevational view thereof, the right side elevational view being a mirror image thereof.

FIG. 6 is a top plan view thereof; and,

FIG. 7 is a bottom plan view thereof.

The broken lines are for illustrative purposes only and form no part of the claimed design.
